UNITED STATES PATENT OFFICE.

MICHAEL S. COLE, OF NEW YORK, N. Y.

CIGAR-HOLDER.

1,081,889.

Specification of Letters Patent.

Patented Dec. 16, 1913.

Application filed February 25, 1913. Serial No. 750,662.

To all whom it may concern:

Be it known that I, MICHAEL S. COLE, a citizen of the United States, residing at New York, in the county of New York and State 5 of New York, have invented new and useful Improvements in Cigar-Holders, of which the following is a specification.

This invention is an improved cigar holder embodying a mouth piece and spring 10 actuated jaws to engage a cigar in the mouth piece and hold the same therein, the object of the invention being to provide an improved cigar holder which is adapted to hold a cigar so securely therein that there 15 is no danger of the cigar becoming casually dislodged.

In the accompanying drawing:—Figure 1 is a side elevation of a cigar holder constructed in accordance with my invention. 20 Fig. 2 is a sectional view of the same. Fig. 3 is a transverse sectional view of the same on the plane indicated by the line $a-a$ of Fig. 1.

The mouth piece 1 of my improved cigar 25 holder may be of any suitable size and shape and may be made of any suitable material. Near the inner end of the mouth piece, or that end thereof in which the cigar receiving socket is provided, is an annular circumferential groove 2. A ring 3 is arranged in this groove and this ring forms the pivot for a series of jaws 4 each of which is formed at one end with a hook 5 to engage one side of the cigar and at the other end 30 with an arm 6 arranged on one side of the mouth piece. The pivotal portions 7 of the jaws are arranged in radial recesses 8 with which the mouth piece is provided and which communicates with the annular 35 groove so that the said jaws are held in place and equidistant around the cigar receiving end of the mouth piece. In connection with each jaw there is a spring 8 which

bears between the arm and the mouth piece and serves to close the jaw against one side 45 of the cigar so that the hooks of the jaws are caused by the action of the springs on the jaws to become embedded in the cigar and thereby the jaws are enabled to securely hold the cigar in place in socket of the 50 mouth piece and prevent the cigar from becoming casually detached. When it is desired to release the cigar, it is only necessary to first press inwardly on the arms 6 of the jaws so as to disengage their hooked ends 55 from the cigar against the tension of the springs.

While I have herein shown and described a preferred form of the invention, I would have it understood that changes may be 60 made in the form, proportion and construction of the several parts without departing from the spirit of the invention and within the scope of the appended claim.

I claim:—

The herein-described cigar holder, embodying a mouth piece having an annular groove near its socket end and radial recesses communicating with said groove, a ring in said groove, jaws pivotally mounted on said ring 70 and having their pivotal portions arranged in said recesses to prevent the ring from turning, each of the said jaws being arranged at one end to engage on one side of a cigar and also having an arm arranged longitudinally on the mouth piece, and springs bearing between said arms and mouth piece, said springs serving to normally engage the jaws with a cigar in the socket of the mouth piece.

In testimony whereof I affix my signature in presence of two witnesses.

MICHAEL S. COLE.
